UNITED STATES PATENT OFFICE.

WILLIAM G. GAGNÉ, OF PORTLAND, MAINE.

VENTILATOR.

No. 920,858.

Specification of Letters Patent.

Patented May 4, 1909.

Application filed June 22, 1908. Serial No. 439,647.

To all whom it may concern:

Be it known that I, WILLIAM G. GAGNÉ, a citizen of the United States, residing at Portland, in the county of Cumberland and 5 State of Maine, have invented a new and useful Ventilator, of which the following is a specification.

This invention relates to improvements in 10 ventilators. Its object is to provide a ven-tilator, simple and cheap in construction and adapted to give a good draft whichever way 15 the wind blows. It is also designed to prevent the escape of cinders and to prevent snow or water falling into the chimney.

15 In the drawings herewith accompanying and making part of this application, Figure 1 is a transverse vertical sectional view of a chimney and my improved ventilator showing one form of the cinder guard; Fig. 2 is a 20 similar view of my invention showing a combined cinder, water and snow guard; and Fig. 3 is a vertical sectional view taken on a line at right angles to the section shown in Fig. 1, showing spacing blocks added.

25 Same letters of reference refer to like parts. In said drawings A represents a pipe or chimney provided with a spherical top B composed of two hollow hemispheres united at the horizontal medial line C. These hemi-spheres are provided with a vertically dis-30 posed series of draft openings D and inter-mediate connecting spaces E integral with the hemispheres. The construction of this top is made simple and cheap by uniting the 35 adjacent edges of the hemispheres in any convenient manner and the hemispheres being unbroken except by the draft openings are very strong and durable. The chimney

A projects upwardly some distance into the 40 bottom of the lower hemisphere as seen at F. Surrounding the hemispheres, spaced apart therefrom and positioned opposite the draft openings, is a shield G somewhat wider than the diameter of said openings. This shield 45 has its lower extremities secured to the chimney below the hemispheres as seen at H and is supported at the top by a bolt I passing through the shield and the hemisphere, and within the hemisphere is mounted a cinder

50 guard K which may consist of a curved band of wire mesh, as shown in Figs. 1 and 3, positioned directly adjacent the draft openings and spaced apart therefrom. The lower ex-tremities are attached to the chimney and its

upper end is supported by means of bolt I. 55 The several parts, hemisphere, shield and guard are thus held in relative position by blocks J interposed between the upper hemi-sphere and the shield and the hemisphere and the guard respectively, thus preventing bend-ing or displacement of the parts. Instead of 60 the wire mesh shown in Fig. 1 the guard may be solid and trough shaped on the outside, as shown in Fig. 2, so that any water or snow passing through the draft openings will col-65 lect in the trough and run down on the out-side of the chimney and thence through open-ings L in the lower hemisphere near the chim-ney.

Having thus described my invention and 70 its use I claim:—

1. A ventilator of spherical form having a series of draft openings therein vertically disposed around said spherical form and spaced apart from each other, a shield out-side of and spaced apart from said spherical form and a guard inside of and spaced apart from said spherical form, said shield and 75 guard being adjacent said openings.

2. A ventilator of spherical form having a series of draft openings vertically disposed around said spherical form and spaced apart from each other and a cinder guard mounted inside of said sphere adjacent to said draft 80 openings and spaced apart therefrom. 85

3. A ventilator of spherical form having a series of vertically disposed draft openings therein spaced apart from each other and a combined cinder and snow guard mounted within said sphere adjacent said openings 90 and spaced apart therefrom, said guard being trough-shaped on its outside.

4. A ventilator of spherical form, a series of vertically disposed draft openings therein, a shield outside thereof, a cinder guard in-side thereof, each spaced apart therefrom, and a bonding bolt passing through the shield, ventilator and guard and spacing blocks interposed between the several parts. 95

In testimony whereof, I have signed my 100 name to this specification in presence of two subscribing witnesses this 18th day of June, 1908.

WILLIAM G. GAGNÉ.

In presence of—

ELGIN C. VERRILL,
MARION RICHARDS.
